D12-203. OR D 13,417 EX

No. 13,417

Nov 14, 1882

UNITED STATES PATENT OFFICE.

JOHN L. POPE, OF CLEVELAND, OHIO.

DESIGN FOR A CARRIAGE-STEP.

SPECIFICATION forming part of Design No. 13,417, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and 5 original Design for Carriage-Steps, of which the following is a specification, reference being had to the accompanying photographic illustration, forming part thereof.

My invention relates to a new design for 10 carriage-steps; and it consists mainly in ornamenting the upper surface thereof with four elliptical-shaped figures, formed of ribbed work, each crossing the other; and it further consists in adorning the outer edges of the 15 step with a curved-shaped border of ribbed or raised work terminating in rounded arch-like figures at each corner of the plate, all as will be hereinafter more fully described and claimed.

20 In the accompanying photograph, *a a a a* represent four elliptical-shaped figures made up of ribbed work, which, as will be plainly seen, cross each other near the middle of the plate and form in the center of the plate a sort of 25 diamond-shaped figure with curved sides and four contiguous triangular-shaped figures. Within the diamond-shaped and triangular

figures I have shown the metal as cut out, and within the former I have shown a foliated opening, while in the latter I have illustrated triangular openings. Near the four upper edges of the step I have designed a curved border of raised work, *b b' b' b'*, &c., that terminates in rounded arch-like figures *c c c c* at each corner, and within the latter figures I have shown round 35 openings; but these, as well as the other openings referred to, are not essential to the novelty of my new pattern, nor is the trefoiled adorment seen at *d d d d*.

What I claim as new, and desire to secure by 40 Letters Patent, is—

1. A design for a carriage-step, consisting of 45 four elliptical-shaped ribbed figures crossing each other, substantially as shown.

2. A design for a carriage-step border, consisting of curved ribs terminating at each corner of the step in rounded arch-like figures, substantially as shown.

In testimony whereof I have hereunto set my hand this 31st day of May, 1882.

JOHN L. POPE.

In presence of—

A. A. POPE,
C. M. COPP.
